DESIGN FOR LEATHER OR SIMILAR ARTICLE OF MANUFACTURE

Fred H. Becker and Lester F. Peabody, Girard,
Ohio, assignors to The Ohio Leather Company,
Girard, Ohio, a corporation of Ohio

Application September 12, 1938, Serial No. 79,854

Term of patent 3½ years

To all whom it may concern:

Be it known that we, Fred H. Becker and Lester F. Peabody, citizens of the United States, residing at Girard, in the county of Trumbull, State of Ohio, have invented a new, original, and ornamental Design for Leather or Similar Article of Manufacture, of which the following is a specification, reference being had to the accompanying drawing, forming part thereof.

The figure is a plan view of the leather showing our new design.

The design consists of a series of embossed, scale-like figures arranged in groups, said scale-like figures each having a star-shaped depression uniformly arranged near one side thereof as shown.

We claim:

The ornamental design for leather or similar article of manufacture, as shown.

FRED H. BECKER.
LESTER F. PEABODY.
